* cited by examiner

Primary Examiner — Rashida C. Walshon(74) Attorney, Agent, or Firm — Dragon Sun Law Firm, P.C; Jinggao Li, Esq.; Nathaniel Perkins(57) CLAIM

The ornamental design for a shoe cover, as shown and described.

DESCRIPTION

FIG. 1 is a perspective view of a shoe cover showing my new design;

FIG. 2 is another perspective view thereof;

FIG. 3 is a front elevation view thereof;

FIG. 4 is a rear elevation view thereof;

FIG. 5 is an enlarged left elevation view thereof;

FIG. 6 is an enlarged right elevation view thereof;

FIG. 7 is a top plan view thereof;

FIG. 8 is a bottom plan view thereof; and,

FIG. 9 is an enlarged view of the selected portion 9 in FIG. 1.

The broken lines shown in the figures depict portions of the shoe cover that form no part of the claimed design.
